CLAIM

The ornamental design for a pair of handles for game controllers, as shown and described.

DESCRIPTION

FIG. 1 is a perspective view of a pair of handles for game controllers showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the pair of handles for game controllers shown in a first configuration of use; and,

FIG. 10 is an exploded perspective view of the pair of handles for game controllers shown in a second configuration of use.

The dot-dash broken lines in the drawings depict environment and form no part of the claimed design. The dash-dash broken lines in the drawings depict portions of the pair of handles for game controllers that form no part of the claimed design.

1 Claim, 10 Drawing Sheets
